METHOD OF REMOVING INSULATING COATINGS FROM WIRES

John A. Orme, Los Angeles, Calif.

Application June 3, 1950, Serial No. 166,005

5 Claims. (Cl. 117—231)

This invention relates to and has for an object the provision of a simple and effective apparatus and method for removing insulating coating from wires.

In modern electrical practice, especially in the production of fine wires such as are used for relays, electromagnets and other purposes, enamel coatings are used for insulating the wires in order that a coil may be formed which will be of a minimum size for a given output or function and closely wound and yet adjacent windings completely insulated against short circuits. It is necessary, however, that terminal portions of the wires, and frequently intermediate portions of the wires, be stripped of their insulation in order to provide positive electrical connections in a system.

In such instances various devices and methods have been employed which while affording desired results, have required the use of cumbersome and more or less complicated apparatus, unnecessary expense and unjustifiable time. In some cases the insulated wires have been heated in ovens to an extent required for dissipation of the insulation, subjected to direct application of heat from a flame, or immersed in molten solder. While such methods may have merely sufficed to remove insulation from the wires, none of them have been completely satisfactory and I have ascertained by protracted experimentation that such insulating coatings are readily removable by the use of an extremely simple expedient which does not require skilled operators and is very inexpensive.

In its broadest aspect my invention includes the use of a crystalline mineral substance acting as a soldering flux which when applied to an enamel insulated wire under direct heat from a presoldered iron simultaneously loosens the insulation and tins the treated section of a wire, while the insulation is loosened and removed. I have ascertained that sal-ammoniac meets the requirements of such

Another broad aspect of my invention includes the application of a hydroxide such as potassium hydroxide (KOH) or sodium hydroxide (NaOH) and heat to a section of wire from which it is desired to remove the insulation. But due to the peculiar properties of said elements, their susceptibility to and disintegration in the presence of moisture, they are difficult to handle and control. Hence it is an object to provide a simple apparatus which will support a cartridge of either of said elements under moisture proof conditions while at the same time rendering the hydroxide immediately available in necessary quantities to meet all demands of insulation removing operations and without possibility of contact with the moisture laden atmosphere.

To such end I have provided a miniature apparatus including a chambered base in which a cartridge of crystalline hydroxide is sealed by a suitable readily fusible wax but arranged at an opening of said chamber with a pervious closure which is always sealed with the wax except during an insulation removing operation when the wax is fused by heat and allows the release of minute but sufficient quantities of the hydroxide in the form of

2

fluid or vapor for attack upon the insulating coatings of wires which overlie the pervious closure.

An ordinary soldering iron or any piece of heated metal is placed upon the wire and the heat therefrom fractures or loosens the insulating coating of the wire so that the chemicals released from the cartridge will rise through the fluid wax and closure and will penetrate the fractures of or enter beneath the insulating coating and dislodge and dissipate the particles of insulating material from the wire without necessity of stripping except with a cloth or brush.

Another object is to provide means for forcing the gradually used cartridge toward the pervious closure so that the cartridge may be completely used before replacement.

A further object is to provide means on the base for firmly supporting the pervious closure at the top of the cartridge chamber and an impervious closure at the bottom of said chamber if one is necessary so that one or both closures may be removed or replaced and yet held in sealed positions at opposite ends of the chamber for preventing entrance of moisture to the chamber which would tend to change the hydroxide from a crystalline to a fluid state.

Other objects may appear as the description of my improvements progresses.

I have illustrated in the accompanying drawings a preferred form of apparatus for attaining the aforesaid objects in which:

Fig. 1 is a perspective view of a suitable apparatus showing an end portion of a wire positioned thereon for treatment by my method;

Fig. 2 is a vertical elevation of a section of the apparatus;

Fig. 3 is a top plan view of the same;

Fig. 4 is a sectional plan on line 4—4 of Fig. 2;

Fig. 5 is a fragmentary section of wire with insulated covering before treatment; and

Fig. 6 is a similar view of a wire showing a portion thereof after removing the insulation therefrom.

In its simplest form I am able to practice the invention by the provision of a base B formed of vitreous or heat resistance material, a cartridge C mounted in a bore 2 of the base, a pervious closure D mounted at the top of bore 2 beneath a narrow inwardly projecting flange 3 and overlying cartridge C and a spring S compressed between the lower end of cartridge C and a retaining disc E held inwardly of an internal annular flange 4 at the bottom of the base. The cartridge C is formed of a crystalline sal ammoniac or potassium hydroxide (KOH) or sodium hydroxide (NaOH) and when a hydroxide is used has a coating of fusible wax F over its periphery and also over its upper end adjacent screen D and lower end. The retaining disc E may be also sealed in its position with wax therebelow and within the shallow chamber 5 of the base so that moisture from the atmosphere cannot enter the bore 2 from any point and cause the disintegration of the cartridge C.

When a unit is formed, as shown in Figs. 1 and 2, in an upright position upon a supporting surface, a wire W, which is insulated with an applied enameled coating, is laid with the terminal portion upon screen D adjacent to an inorganic chemical flux and a hot iron, such as a presoldered iron G, is laid upon the terminal portion of the wire and serves to melt the wax coating F of the top and apply heat to the cartridge C and thereby release an inorganic chemical flux such as sal ammoniac or hydroxide in the form of vapor or liquid for attack upon the terminal portion of the wire. The heat from iron G expands and fractures or at least loosens the enamel coating on the portion of the wire being treated and per-

3
mits the entrance of the hydroxide vapor or liquid under the coating so that it may be readily wiped off with a brush or cloth leaving the terminal portion of the wire completely stripped of its insulation.

It is apparent that as the quantity of chemical in the cartridge is depleted by frequent use, the tension of spring S urges the cartridge C into contact with the screen so that the upper end of the cartridge is always adjacent said screen until the cartridge has been completely used.

The wax coating over the top of the cartridge, upon removal of iron G, flows back over the screen and seals the orifices therein so as to exclude moisture until heat again is applied upon another wire stripping operation.

An advantage of my apparatus and method is in the fact that the sal ammoniac or hydroxide serves as a flux which facilitates cohesion between the solder and the wire so that so-called tinning of the wire is accomplished in the same operation required to strip the insulation therefrom.

The essence of the invention, therefore, is the provision of simple, convenient and economical means for stripping insulating enamel from sections of wire by the simultaneous application of heat for loosening the enamel and a suitable flux to the treated portion of the wire for so loosening the enamel that it may be readily wiped off.

I claim:

1. A method of removing insulating enamel from wire which comprises placing a portion of a wire to be denuded of enamel adjacent to a solid inorganic soldering flux, and applying a hot metal member to said wire in 30 order to loosen the enamel coating on said wire and to apply heat to said flux so as to cause said flux to loosen said enamel.

2. A method as defined in claim 1 wherein said in- 35
organic flux is potassium hydroxide.

3. A method as defined in claim 1 wherein said in-
organic flux is sodium hydroxide.

4. A method as defined in claim 1 wherein said in-
organic flux is sal ammoniac.

5. A method for removing insulating enamel from a portion of a wire and tinning said portion of said wire which comprises placing a portion of a wire to be denuded of enamel adjacent to a solid inorganic soldering flux, and applying a hot presoldered iron to said portion for loosening and removing the enamel from said portion of said wire, and applying solder to the treated portion of the wire simultaneously with the removal of said enamel.
